PAWL-AND-RATCHET MECHANISM.

No. 824,963.

Specification of Letters Patent.

Patented July 3, 1906.

Application filed October 17, 1904. Serial No. 228,771.

To all whom it may concern:

Be it known that I, WILLIAM TREWHELLA, a subject of the King of Great Britain, residing at Trentham, in the State of Victoria, 5 Commonwealth of Australia, trading with Benjamin Trewhella, a subject of the King of Great Britain, residing at Trentham, aforesaid, as Trewhella Bros., engineers and iron-workers, have invented an Improved Pawl-and-Ratchet Mechanism, of which the following is a specification.

This invention has relation to pawl-and-ratchet mechanisms, especially applicable to lifting-jacks and winches.

15 A characteristic feature of the invention lies in the combination, with a ratchet-toothed element, which may be movable or stationary, of two actuating-pawls and means for imparting reciprocal motion thereto to move said element or to move an element carrying the pawls.

20 A further characteristic feature of the invention lies in means for holding the pawls in contact with the ratchet-toothed face of said stationary or movable element.

25 A further characteristic feature of the invention lies in a loose connection of the pawls with the element which serves to reciprocate the same and in combination therewith of means to maintain said connection and at the same time maintain the pawls in contact with the ratchet-toothed face of the movable or stationary element.

30 A still further characteristic feature of the invention lies in means for reversing the direction of motion of the ratchet-toothed element or of the element which carries the pawls, and, lastly, in the provision of a segmental rocking bearing for the element which imparts reciprocal motion to the pawls; but that my invention may be fully understood I will describe the same in detail, reference being had to the accompanying drawings, in which—

35 Figure 1 is a vertical sectional view illustrative of the application of my invention to a lifting-jack of that type in which the rack-bar is movable. Fig. 2 is a side elevation, the face-plate of that part of the casing containing the pawl mechanism being removed, illustrating the application of my invention to a lifting-jack having a stationary rack-bar and movable load-supporting casing. Fig. 3

is a fragmentary sectional view illustrative of the application of the invention to the ratchet-wheel of a winch or the like. Figs. 4 and 5 are fragmentary sectional views of Fig. 1, illustrative of the operation of the disengaging-lever in reversing the direction of motion of the rack-bar. Fig. 6 is a section on line VI VI of Fig. 1, and Fig. 7 is a fragmentary perspective view of parts shown in Figs. 1 to 5.

Referring more particularly to Fig. 1, *c* indicates the stationary casing in which the rack-bar 7 has free vertical movement. The casing is of suitable construction to contain the pawls and pawl-actuating mechanism and has preferably two openings *o* and *o'*, Fig. 2, on one side, normally closed by a face-plate *p*, Fig. 6, to afford ready access to said mechanism, in which is mounted a rock-shaft 1, hereinafter referred to as the "rocker."

In the construction of jack under consideration the rocker 1 supports the load, and bearings of sufficient strength must be provided. To avoid undue increase of the thickness of the casing or the connection thereto of bearings or journal-boxes, I provide a sectoral rocking bearing 23, whose convex face 22 bears on and rocks with the rocker 1. The lower end 24 of the web of the rocking bearing is rounded and may be stepped in a corresponding step, formed by the lower contracted portion of the walls of the casing-chamber *c'*. I prefer, however, to step said bearing in a suitable wear-plate 24^a, bolted to the casing, so that it may readily be removed. The front and back walls of the casing-chamber *c'* may serve to limit the rocking movements of the bearing 23, or pins or studs 26 may be provided for the purpose, as shown. The rocker 1 has a partial peripheral groove and nearly circular recesses 3 for the reception of the nearly circular foot ends of two pawls 5 of different lengths, said recesses being formed on opposite sides of the center of oscillation of the rocker 1 and at such angles to said center as to impart to the pawls reciprocal movements which in the case under consideration are equal to the space between two teeth 6 on the rack-bar 7, said rocker being provided with a crank 2, Figs. 2, 4, and 5, as one means of oscillating the same. By stepping the pawls in the

95

100

105

rocker 1 can dispense with pivot-pins and am enabled to readily remove said pawls, if this becomes necessary.

To prevent longitudinal movement of the pawls and at the same time maintain their free ends constantly in contact with the ratchet-toothed face of the bar, except when moved out of contact therewith for purposes hereinafter described, said pawls are pivotally connected near the rocker to one end of two connecting-rods 10, whose opposite ends are pivotally connected to opposite ends of a balance-lever 9, mounted in the free end of an arm 11, pivoted on a fixed pin 12, on one end of which is loosely mounted a disengaging-lever 16, hereinafter referred to.

On the pin 12 is mounted a coiled spring 13, one end, 14, of which exerts a pressure on the arm 11 by which the pawls 5 are held against longitudinal movement and also in contact with the ratchet-toothed face of the rack-bar 7 through the balance-lever 9 and links 10 and yet permit reciprocal motion of said pawls, each of which is provided with a pin or stud 19, adapted to be engaged by the inclined faces 18 of two lugs or projections 17 and 17^a on the disengaging-lever 16, above referred to, on which the other end, 15, of spring 13 exerts pressure.

On the inner end of a stud or pin projecting through one of the lateral walls of the casing-chamber *c'* is secured an eccentric or cam 20, Fig. 6, (also shown in dotted lines, Fig. 3,) adapted to engage the disengaging-lever and move it laterally, so that its lugs 17 and 17^a will be out of reach of the pins 19 on the pawl 5, in which position said lever is held, as shown in Fig. 1, when the rack-bar 7 is being moved upward.

The operation of the jack is as follows: Assuming both pawls 5 in engagement with the rack-bar 7 and the rocker 1 rocked from right to left, the shorter pawl will lift said rack-bar a distance equal to the space between two

teeth 6, while the longer pawl will move down a corresponding distance and engage the tooth next below. By reversing the direction of oscillation of the rocker 1 the longer pawl will lift and the shorter pawl will move

down and engage the tooth next below, so that at each oscillating movement the rack-bar 7 will be raised a distance equal to the space between two teeth, the operation being the same in the application of the pawl mechanism to the ratchet-wheel 8 of a winch, Fig. 3, or the like. In either case the pawls are constantly held in contact with the ratchet-toothed face of a movable element 7 or 8 by the action of the spring 13 on arm 11 and the

action of the latter on the connecting-rods 10 through the balance-lever 9, which is free to follow the movements of the pawls. To reverse the direction of motion of the ratchet-toothed element, it is, however, necessary that the pawls 5 be alternately moved out of

contact with said element. To this end the eccentric 20 is thrown back and the disengaging-lever 16 is released, so that it may swing into operative position under the action of the spring 13, as shown in Figs. 4 and 5. Referring to Figs. 4 and 5 and assuming that both pawls are in engagement with the rack-bar, as shown in Fig. 1, the eccentric 20 is turned so as to disengage the lever 16, when the latter will swing to the left under the action of the spring 13, and the lug 17^a will engage the pin 19 of the short pawl 5 and move said pawl to the left free from engagement with the rack 7, the weight of the rack having been brought on the long pawl by a slight movement of the rocker to the right, Fig. 4. If the rocker 1 is now oscillated from right to left in the direction of the arrow, Fig. 4, the shorter pawl 5 will move upward with its pin 19 riding up the lug 17^a on lever 16 and engage a tooth of the rack-bar 7. At the same time the longer pawl moves down with its pin 19 riding down the lug 17 on the lever 16, which movement carries it out of contact with the rack-bar 7, as shown in Fig. 5. If now rocker 1 is reversed—that is to say, oscillated from left to right—the long pawl will move upwardly with its pin 19 riding up lug 17 and into engagement with a tooth of the rack-bar 7. Simultaneously with this movement of the longer pawl 5 the short pawl moves down, its pin 19 riding down the inclined face of lug 17^a on lever 16 and out of engagement with the rack, at which time the long pawl will be in engagement with a tooth on the rack-bar and the bar lowered by one tooth. By again reversing the rocker in the direction of the arrow, Fig. 4, the short pawl will be moved into contact with the rack-bar, as described, the pawls being alternately moved into and out of contact with the rack-bar to lower the latter tooth by tooth, a uniform and reliable movement being thus obtained.

From the above description the operation of reversing the ratchet-wheel 8, Fig. 3, can be readily deduced.

In the application of the described mechanism to a lifting-jack having a stationary rack-bar and a movable load-support the said mechanism is simply inverted, so that by the operation of the pawls the casing *c'* will be caused to move up or down the rack-bar, as will be readily understood.

Having thus described my invention, what I claim as new therein, and desire to secure by Letters Patent, is—

1. A pawl-and-ratchet mechanism comprising a ratchet-toothed element, two actuating-pawls, and means to impart reciprocal motion to said pawls; in combination with means to normally maintain the actuating-faces of the pawls in contact with the toothed face of said ratchet-toothed element, comprising a spring-actuated pivoted arm, a balance-

lever carried thereby and connecting-rods connecting each end of said lever with an actuating-pawl.

2. A pawl-and-ratchet mechanism, comprising a ratchet-toothed element, an oscillating element and two actuating-pawls engaging the teeth of said ratchet-toothed element and connected to the oscillating element on opposite sides of its center of oscillation to impart reciprocal movements to the pawls; in combination with a spring-actuated pivoted arm, a balance-lever carried thereby, and connecting-rods connecting each end of the balance-lever with an actuating-pawl.

3. In a pawl-and-ratchet mechanism, the combination of a casing, a single rack, a cylindrical oscillating element, two pawls mounted on the latter, and a rockable sector mounted in the frame of the casing on which the oscillating element is adapted to roll.

4. A pawl-and-ratchet mechanism, comprising a ratchet-toothed element, an oscillating element, two pawls connected thereto at opposite sides of its center of oscillation to impart reciprocal motion to the pawls, a spring-actuated pivoted arm, a balance-lever carried thereby and connecting-rods connecting each end of said lever to a pawl to maintain them in contact with the ratchet-toothed element; in combination with means for moving the pawls alternately out of contact with the ratchet-toothed element, for the purpose set forth.

5. A pawl-and-ratchet mechanism, comprising a ratchet-toothed element, an oscillating element, two pawls connected thereto at opposite sides of its center of oscillation to impart reciprocal motion to the pawls, a spring-actuated pivoted arm, a balance-lever carried thereby, and connecting-rods connecting each end of said lever to a pawl to maintain them in contact with the ratchet-toothed element; in combination with means adapted to be brought into operation at will for moving the pawls alternately out of contact with the ratchet-toothed element, for the purpose set forth.

6. A pawl-and-ratchet mechanism, comprising a ratchet-toothed element, an oscillating element, two pawls connected thereto at opposite sides of its center of oscillation to impart reciprocal motion to the pawls, a spring-actuated pivoted arm, a balance-lever carried thereby, and connecting-rods connecting each end of said lever to a pawl to main-

tain them in contact with the ratchet-toothed element; in combination with a spring-actuated disengaging-lever adapted to alternately engage the pawls and move them out of contact with the ratchet-toothed element, and means to lock said lever against operation.

7. A pawl-and-ratchet mechanism, comprising a ratchet-toothed element, an oscillating element, two pawls connected thereto at opposite sides of its center of oscillation to impart reciprocal motion to said pawl, each provided with a laterally-projecting pin 19, a spring-actuated pivoted arm, a balance-lever carried thereby and connecting-rods connecting each end of the lever to a pawl to maintain them in contact with the ratchet-toothed element; in combination with a spring-actuated disengaging-lever provided with two lugs, 17 and 17^a having inclined faces 18 adapted to engage the pins 19 on the aforesaid pawls and move the latter alternately out of contact with the ratchet-toothed element when the oscillating element is rocked to and fro, and means to lock said lever against operation, for the purpose set forth.

8. The combination with the rocker 1, its carrier, the long and short pawls having laterally-projecting pins 19 and connected to the rocker as described, and a ratchet-toothed element engaged by said pawls; of the pivoted arm 11, the balance-lever 9 carried thereby, the connecting-rods 11 connecting each end of said balance-lever to a pawl, the disengaging-lever 16 having two lugs, 17 and 17^a and loosely mounted on pivot of arm 11, and the spring 13 coiled on said pivot one end of which exerts power on said arm and the other on the disengaging-lever, substantially as and for the purpose set forth.

9. In a pawl-and-ratchet mechanism, the combination of a single rack, a cylindrical oscillating element, two actuating-pawls mounted on the oscillating element, and means to move both pawls into and out of engagement with the rack, a casing having a chamber formed therein, and a rockable sector mounted in said chamber on which the oscillating element is adapted to roll.

In testimony whereof I have hereunto set my hand in presence of two subscribing witnesses.

WILLIAM TREWHELLA.
